UNITED STATES PATENT OFFICE.

FRANKLYN J. WOLFF, OF TRENTON, NEW JERSEY.

BLANK-TRANSFER MECHANISM FOR SAGGER-MAKING MACHINES.

Application filed May 7, 1920. Serial No. 379,549.

To all whom it may concern:

Be it known that FRANKLYN J. WOLFF, a citizen of the United States of America, residing at Trenton, in the county of Mercer and State of New Jersey, has invented new and useful Improvements in Blank-Transfer Mechanism for Sagger-Making Machines, of which the following is a specification.

10 In the construction of saggers, employed in the pottery art as containers or protectors for articles during the baking or annealing operation, it has been found expedient as a means for securing walls of homogeneous 15 structure contemplating a body or vehicle of clay, or its equivalent, with a granular filler uniformly distributed and thoroughly incorporated to produce from the batch a sheet or continuous slab of the required 20 thickness and width by forcing the plastic material directly from the mixing apparatus through a progressively modified reforming outlet or nozzle, as disclosed in co-pending application No. 298,155 filed May 19, 25 1919, Patent No. 1,337,871 and in order that the sheet or slab forming mechanism may operate continuously as the sagger elements or parts formed from the sheet or slab are being assembled preparatory to burning, or 30 in other words to avoid interruption of the mixing and sheeting mechanism during a "run" or period devoted to the construction of saggers, it is the object of this invention to provide apparatus for facilitating the removal of suitable sections, lengths, or blanks 35 of the plastic sheet or slab from the forming mechanism and transferring it expeditiously and without risk of distortion, strain, or fracture to an assembling or delivery station in proper position and condition to be 40 handled manually in the further pursuance of the operation of assembling; and incidentally to facilitate the placing of the blanks in a smooth and normal condition 45 upon pallets so that they may be moved by hand in arranging the blanks in their proper relative position to form saggers, and to affect a transfer of the blanks from the table at the receiving station to suitable reversing 50 mechanism and from the reversing mechanism to a table or like support or rest at the delivery station with a minimum of resistance and without involving or necessitating pushing or pulling strains applied to the 55 blank to overcome resistance caused by the

friction of the slab with the supporting surface or to the stretching impulse of gravity, and hence without tendency to modify either the shape or dimensions of the blanks or sections during the interval between the delivery of the sheet or slab from the forming mechanism and the deposit of the same at the delivery station, and during which interval the locating of the blank upon the pallet or carrying part is effected.

With this and related objects in view as will appear in the course of the following description of one embodiment of the invention, the same consists of a construction, combination and relation of parts disclosed in the accompanying drawings, it being understood that changes in form, proportion and details of arrangement may be resorted to within the scope of the appended claims, without departing from the principle involved.

In the drawings Figure 1 is a plan view of the blank transferring apparatus showing the same in operative relation with the sheet or slab forming mechanism.

Figure 2 is an elevation of the reversing mechanism in its position in operation or receiving position in relation to the sheet forming mechanism.

Figure 3 is an end view showing the delivery station and its related parts in side elevation and the reversing mechanism in the position which it occupies when receiving a blank from the sheet forming mechanism.

Figure 4 is a detail sectional view of one end of the reversing mechanism.

Figure 5 is a detail view of one of the pallets or carrying parts.

Figure 6 is a detail view of the preferred mounting of the carrying wheels which support the reversing table.

Figure 7 is a detail view in elevation of the delivery spout or nozzle of the sheet or slab forming mechanism viewing the same on a plane indicated by the lines 7—7 of Figure 2.

Figure 8 is a detail sectional view on the plane indicated by the lines 8—8 of Figure 1.

Figure 9 is a vertical view showing the relation of the nozzle, the receiving table, and the supporting wheels of the reversing mechanism.

The apparatus consists essentially of a receiving station indicated at A and delivery

station indicated at B and a reversing mechanism represented generally at C, the receiving station being located in operative relation with a sheet or slab forming mechanism indicated at D.

The sheet forming mechanism may consist of a pug mill 10 of any suitable or well known construction designed to properly and thoroughly mix the ingredients entering into the composition of the sagger walls and other elements and provided with an outlet or sheet forming spout or nozzle 11 through which the plastic material is advanced under suitable pressure to present it in the form of a continuous sheet or slab to the receiving station which in the construction illustrated consists essentially of a table 12 provided with an endless carrier 13 in the form, for example, of an apron or conveyor carried by suitable rollers 14' and disposed at a slight inclination downward in the direction indicated by the arrow *a* to the end that the sheet of material as it exudes from the nozzle is inclined to traverse the table progressively under the combined influence of the sheet forming pressure within the forming mechanism and gravity, in order that neither pushing nor pulling effect may be produced or is necessary to induce or cause such progressive movement, and hence in order that the possibility of distorting the sheet or slab either by condensing or stretching the same may be minimized. It is proposed to secure an easy or free advance of the sheet or slab under conditions which will insure the accurate maintenance of the dimensions as to thickness and width defined by the outlet of the nozzle.

From time to time, as the sheet or slab advances upon the receiving table, portions thereof, suitable respectively to constitute blanks for the walls of saggers, are detached from the sheet and moved from the receiving table to a reversing table 13^a forming a part of the reversing mechanism and also disposed preferably at a slight downward inclination from the receiving end towards the opposite end, said reversing table being movably supported by wheels 14 with relation to which the receiving table occupies a substantially diametrical position, to the end that when the transfer mechanism is in the position indicated in Figures 1 and 2 in receiving relation with the receiving station, one side of the reversing table will be uppermost, whereas when the reversing mechanism is moved upon its supporting wheels or rollers to a position in operative relation with the delivery station as indicated in dotted lines in Figure 3, the uppermost section of the table will be directed downwardly to effect the transfer of an object supported by its original upper surface to a receiving surface represented in the con-

struction illustrated by a transfer table 15 forming an element of the delivery station.

The reversing table preferably extends at one end through the open center of the supporting wheel which is adjacent to the receiving table 12, as indicated in Figure 4 to the end that when the reversing mechanism is in the receiving position as shown in Figures 1 and 2, a blank separated from the sheet or slab on the carrier of the receiving table may readily be transferred to a similar carrier 16 consisting of an endless apron on the reversing table, and when this transfer to the reversing table has been effected a pallet or carrying board 17, shown in detail in Figure 5 and stacked for the convenience of the operator as shown in Figure 3 is placed with its uniform or smooth surface downward upon the upper exposed surface of the blank as indicated in Figure 2 and is secured in such relation to the blank by means of holding means consisting in the construction illustrated of pivotal clamping members 18 mounted upon the reversing table for engagement with ears 19 projecting laterally from the edges of the pallet.

The reversing mechanism is then moved upon its supporting wheels or rollers 14 from the receiving position indicated in Figures 1 and 2 and in full lines in Figure 3 to the delivery position indicated in dotted lines in Figure 3 in operative relation with the delivery station, during which movement the table 13^a is reversed or inverted to dispose the previously placed pallet undermost, or in other words with the blank bearing upon and supported by the pallet, and in this relation of the parts the movement of the pallet from the reversing mechanism to a delivery table 20 may be effected without disturbing or distorting the blank supported thereby.

However, in order that the transfer of the blank carrying pallet from the reversing table to the delivery table 20 may be effected without jarring the pallet in such a way as to involve the risk of distorting the blank, it is preferred to employ in connection with the delivery station a transfer table 15 which is mounted to tilt upon an axis 21 supported by suitable standards 22 with the end thereof which is adjacent to the delivery table 20 counter-weighted or overbalanced so that such transfer table normally and yieldingly occupies the position indicated in full lines in Figure 3. The transfer table is preferably provided with a carrier of suitable antifrictional form such as the rollers 23 for receiving the pallet, and the receiving end of the transfer table, which is free to be depressed from the full line position indicated in Figure 3 to the dotted line position indicated in the same figure, and in the path of which is arranged

the stop 24, is adapted to be engaged by the reversing table as the latter approaches the transfer table to dispose the latter at an inclination corresponding in substantial parallelism with the reversing table, so that as the latter reaches the limit of its movement the pallet is in a position to be laid upon the transfer table practically without jar or shock. As soon as the free outer end 10 of the transfer table is relieved of the pressure of the reversing table, or of such means in connection therewith as may serve to move the transfer table to its blank receiving position (shown in dotted lines in Figure 3) the counter-balanced inner end of the transfer table serves to return the latter to its normal position indicated in full lines in Figure 3 in which it is inclined slightly downward towards its delivery end or that 20 end which is adjacent to the delivery table 20, to the end that the blank carrying pallet may be induced to move toward the delivery table from which it may be removed by attendants having the duty of assembling the 25 blanks to form saggers.

In order that the blank carrying pallet after deposit upon the tilting transfer table may be retained in position until the release of the latter by the reversing mechanism 30 may permit the return of the transfer table to its normal position, it is preferable to employ in connection with the transfer table a pallet holding means such as a retaining arm 25 provided with detent 26 which is 35 brought into operative relation with the surface of the transfer table by the depression of the outer or receiving end thereof, and which serves to engage the pallet and remain in engagement therewith during the 40 return movement of the transfer table to its horizontal position.

In order that the locking of the pallet in position upon the reversing table, in contact with the initially exposed or upper surface 45 of the blank, and the disengagement of the pallet when it reaches the delivery station may be effected automatically, and without specific action on the part of the operator, it is preferred to provide means in the nature of trip mechanism for moving the locking members 18 to their disengaged position at the limits of movement of progress of the reversing mechanism, said retaining arms being yieldingly propelled toward pallet 50 locking position by means of springs 27, and in the construction illustrated such trip mechanism consists of flexible runners 28 and 29 connected with the arms 18 and extending around direction pulleys 30 and 60 guide pulleys 31, the portions of the runners between the guide pulleys, in diametrically opposite positions with relation to the carrier wheels, being exposed for contact with trip blocks 32 and 33 with which they engage as the reversing mechanism respec-

tively reaches the limits of its movement in opposite directions. Obviously when the reversing mechanism reaches the receiving position with its table in registration with the receiving table 12 of the receiving station, 70 the portion of the runner 28 between the guide pulleys 31 will come in contact with the stop 32 and thus retract the locking arms 18 to permit the disposing of the pallet upon the blank resting upon the reversing table 75 with its ears disposed within the paths of said locking arms, and as the reversing mechanism is moved towards the delivery station said locking arms will be released and will engage the ears 19 to hold the pallet in blank receiving position during the reversing operation. When the reversing mechanism reaches the delivery station and the transfer table is tilted as above described to receive the blank, the corresponding portion of the runner 29 will engage the stop 80 33 and thus release the pallet to permit it to rest upon the surface of the transfer table from which it is conveyed as previously described to the delivery table 20. 90

In order that the movement of the reversing mechanism may be accurately timed and controlled with relation to the interval between the receiving and delivery stations, to the end that the operative parts or elements of the mechanism may be in their proper relations respectively when the reversing mechanism reaches its limits of movement, it is preferable to employ gear 95 wheels as illustrated as the supporting elements of the reversing table, and racks or toothed tracks 34 for traverse by said gears as clearly indicated in Figures 1, 3 and 6. 100

Moreover in order that the sheet or slab may be divided or slotted longitudinally as it is discharged from the sheet forming nozzle, to produce blanks of varying widths to suit saggers of different dimensions and minimize the manual treatment of the blanks in adapting them to the formation 110 of saggers and like receptacles of the various dimensions required in the pottery art, it is preferable to provide the nozzle 11 at its orifice with a plurality of spaced seats 35 for the interchangeable or selective reception of cutter wires 36 suspended from a suitable support 37 and provided at their lower ends with suitable weights 38 or like tensioning means. Obviously the construction indicated provides the optional use of 115 this slitting or longitudinally cutting means, and for the arrangement of any desired number of the elements thereof in the desired relative position to effect a slitting of the sheet or slab to form strips of the required width from which the blanks for saggers may be subsequently detached by transverse cuts which obviously may be effected by any suitable cutting tool not constituting a feature of the present invention. 120 130

The invention having been described as being what is new and useful is:

1. A blank transferring and inverting apparatus for sagger forming mechanisms having spaced receiving and delivery stations and a flat blank carrying table automatically reversible and movable between said stations for successively conveying the blanks from the former to the latter during the inversion thereof.
2. A blank transferring and inverting apparatus for sagger forming mechanisms having spaced receiving and delivery stations and a flat blank carrying table automatically reversible and movable between said stations for successively conveying the blanks from the former to the latter during the inversion thereof and provided with means for holding a pallet in contact with the initially exposed surface of a blank seated on said table during the reversal of the latter.
3. A blank transferring apparatus having respectively receiving and delivery stations and a reversible transfer table progressively movable between said stations during inversion, the delivery station having a tilting transfer table for arrangement in parallelism, with the reversible table at the delivery terminus of the progressive movement of the latter.
4. A blank transferring apparatus having respectively receiving and delivery stations and a reversible transfer table progressively movable between said stations during inversion and provided with means for holding a pallet in receiving relation with a blank in transit between stations, the delivery station having a tilting transfer table for arrangement in parallelism with the reversible table at the delivery terminus of the progressive movement of the latter.
5. A blank transferring apparatus for sagger forming mechanism having respectively receiving and delivery stations and a reversible transfer table progressively movable between said stations, the delivery station having a tilting transfer table for engagement by the reversible table at the delivery terminus of its progressive movement.
6. A blank transferring apparatus for sagger forming mechanism having respectively receiving and delivery stations and a reversible transfer table progressively movable between said stations, the delivery station having a counter-balanced tilting transfer table for movement into parallelism with the reversible table at the delivery terminus of the progressive movement of the latter.
7. A blank transferring apparatus for sagger forming mechanism having a reversible progressively movable table for successively receiving the blanks from the sheet forming mechanism, a delivery table toward which the reversible table moves for deposit of the blanks and a tilttable transfer table arranged in the path of the reversible table for arrangement in receiving and delivering relations respectively with reference to the reversible table and the delivery table.
8. A blank transferring apparatus for sagger forming mechanism having a reversible progressively movable table for successively receiving the blanks from a sheet forming mechanism, a delivery table toward which the reversible table moves for deposit of the blanks, and a tilttable transfer table arranged in the path of the reversible table for arrangement in receiving and delivering relations respectively in reference to the reversible table and the delivery table, and actuatable by the reversible table to assume its receiving position.
9. A blank transferring apparatus for sagger forming mechanism having a reversible progressively movable table for successively receiving blanks from the sheet forming mechanism, and a delivery table toward which the reversible table moves for deposit of the blanks, and a tilting transfer table movable to receiving and delivering positions respectively in relation to the reversible table and the delivery table, said transfer table being yieldingly held in one position and being actuatable by the reversible table to assume the other position.
10. A blank transferring apparatus for sagger forming mechanism having a reversible progressively movable table for successively receiving the blanks from a sheet forming mechanism, a delivery table towards which the reversible table moves for deposit of the blanks, and a tilting transfer table counter-weighted to occupy a delivery position in reference to the delivery table and actuatable by the reversible table to assume a position in receiving relation to the latter.
11. A blank transferring apparatus for sagger forming mechanism having a reversible progressively movable table for receiving blanks from a sheet forming mechanism, a delivery table towards which the reversible table moves for deposit of the blanks, a tilting transfer table movable to occupy receiving and delivering positions respectively in relation to said reversible and delivery tables and pallet holding means for engaging a pallet superposed upon the transfer table.
12. A blank transferring apparatus for sagger forming mechanism having a reversible progressively movable table for successively receiving blanks from a sheet forming mechanism, a delivery table toward which the reversible table moves for deposit of the blanks, a tilting transfer table movable to occupy receiving and delivering positions respectively in relation to said reversible and delivery tables and actuatable by the

reversible table, and pallet holding means for engaging a pallet superposed upon the transfer table.

13. A blank transferring apparatus for sagger forming mechanism having a reversible progressively movable table for successively receiving blanks from a sheet forming mechanism, a delivery table toward which the reversible table moves for deposit of the blanks, a tilting transfer table movable to occupy receiving and delivering positions respectively in relation to said reversible and delivery tables, and pallet holding means active when the transfer table is in its receiving position for engaging a pallet superposed upon the transfer table.

14. A blank transferring apparatus for sagger forming mechanism having a reversible progressively movable table for successively receiving blanks from a sheet forming mechanism, a delivery table toward which the reversible table moves for deposit of the blanks, and a tilting transfer table adapted for inclination in opposite directions to occupy receiving and delivering positions respectively in reference to said reversible and delivery tables.

15. A blank transferring apparatus for sagger forming mechanism having a reversible progressively movable table for successively receiving blanks from a sheet forming mechanism, a delivery table toward which the reversible table moves for deposit of the blanks, a tilting transfer table adapted for inclination in opposite directions to occupy receiving and delivering positions respectively in reference to said reversible and delivery tables, and pallet engaging means operative when the transfer table is in its receiving position.

16. A blank transferring apparatus for sagger forming mechanism having a reversible progressively movable table for successively receiving blanks from a sheet forming mechanism, a delivery table toward which the reversible table moves for deposit of the blanks, a tilting transfer table adapted for inclination in opposite directions to occupy receiving and delivering positions respectively in reference to said reversible and delivery tables, and an alternately operative and inoperative pallet holding means actuatable by the transfer table.

17. A blank transferring apparatus for sagger forming mechanism having a reversible progressively movable table for successively receiving blanks from a sheet forming mechanism, a delivery table toward which the reversible table moves for deposit of the blanks, a tilting transfer table adapted for inclination in opposite directions to occupy receiving and delivering positions respectively in reference to said reversible and delivery tables, and a pallet engaging device disposed in operative relation with

the surface of the transfer table when the latter is in its receiving position.

18. A blank transferring apparatus for sagger forming mechanism having a reversible progressively movable table for successively receiving blanks from a sheet forming mechanism, a delivery table toward which the reversible table moves for deposit of the blanks, a tilting transfer table adapted for inclination in opposite directions to occupy receiving and delivering positions respectively in reference to said reversible and delivery tables, and a pallet engaging device disposed in operative relation with the surface of the transfer table during the movement of the latter from its receiving towards its delivering position.

19. A blank transferring apparatus for sagger forming mechanism having a reversible table for arrangement in receiving relation with the outlet of a sheet forming device, means for holding a pallet in contact with the initially exposed surface of the blank, and a trip mechanism operative to disengage the holding means at the limits of movement of the table.

20. A blank transferring apparatus for sagger forming mechanism having a reversible wheel supported table for receiving blanks from a sheet forming mechanism, normally operative pallet holding means for engaging a pallet superposed upon a blank during the movement of the table and trip devices for disengaging the holding means at the limits of movement of the table.

21. A blank transferring apparatus for sagger forming mechanism having a reversible wheel supported table for movement between receiving and delivery stations and normally active pallet holding clamps for engagement with a pallet during the movement of the pallet between stations and trip mechanism at the stations for actuating the clamp to release the pallet.

22. A blank transferring apparatus for sagger forming mechanism having respectively receiving and delivery stations and a progressively movable blank reversing means for transferring a blank from the former to the latter, and consisting of a table and supporting wheel wherein the former occupies a position substantially in and throughout a diametrical plane of the latter.

23. A blank transferring apparatus for sagger forming mechanism having respectively receiving and delivery stations and blank reversing means for transferring blanks from the former to the latter and consisting of a table and parallel co-axial gear wheels wherein the table is disposed substantially in a diametrical plane of said wheels.

24. A blank transferring apparatus for sagger forming mechanism having respectively receiving and delivery stations and

blank reversing means for transferring blanks from the former to the latter and consisting of a table and parallel co-axial gear wheels wherein the table is disposed substantially in a diametrical plane of said wheels, the table being provided with an endless carrier apron.

25. A blank transferring apparatus for sagger forming mechanism having respectively receiving and delivery stations and blank reversing means for transferring blanks from the former to the latter and consisting of a table and parallel co-axial gear wheels wherein the table is disposed substantially in a diametrical plane of said wheels, the table being provided with an endless carrier apron arranged at a downward inclination from the plane of one wheel and toward that of the other.

26. A blank transferring apparatus for sagger forming mechanism having respectively receiving and delivery stations and blanks reversing means for transferring blanks from the former to the latter and consisting of a table and parallel co-axial gear wheels wherein the table is disposed substantially in a diametrical plane of said wheels, the table being provided with an endless carrier apron arranged at a downward inclination from its receiving toward its opposite ends.

27. A blank transferring apparatus for sagger forming mechanism having respectively receiving and delivering stations provided with carriers and a wheel supported reversing table disposed in diametrical relation to its wheels and progressively movable into receiving and delivery relations alternately with said stations.

28. A blank transferring apparatus for sagger forming mechanism having respectively receiving and delivery stations pro-

vided with carriers movable in paths at right angles to each other and a wheel supported reversible table supported in diametrical relation to its wheels and movable progressively in a fixed path in receiving and delivery relations respectively with said stations.

29. A blank transferring apparatus for sagger forming mechanism having receiving and delivering stations provided with carriers and a wheel supported reversing table disposed in diametrical relation to its wheels and movable into receiving and delivery relations with said stations, the table at the delivery station being disposed at a downward inclination toward its receiving end.

30. A blank transferring apparatus for sagger forming mechanism having receiving and delivery stations provided with carriers and a wheel supported reversing table disposed in diametrical relation to its wheels and movable into receiving and delivery relations with said stations, the table at the delivery station being tilted to occupy a position at a downward inclination towards its receiving end.

31. A blank transferring apparatus for sagger forming mechanism having receiving and delivery stations provided with carriers and a wheel supported reversing table disposed in diametrical relation to its wheels and movable, into receiving and delivery relations with said stations, the table at the delivery station being tilted to occupy a position at a downward inclination towards its receiving end, and said tilted table being movable to its receiving position by said reversible table.

In testimony whereof he affixes his signature.

FRANKLYN J. WOLFF.

Certificate of Correction.

It is hereby certified that in Letters Patent No. 1,452,331, granted April 17, 1923, upon the application of Franklyn J. Wolff, of Trenton, New Jersey, for an improvement in "Blank-Transfer Mechanisms for Sagger-Making Machines," an error appears requiring correction as follows: In the heading to the drawing, line 5, insert 3 Sheets—Sheet 1; Sheets 2 and 3, containing Figures 2, 3, 4, 5, 6, and 9, should appear as follows as part of the Letters Patent:

Apr. 17, 1923.
